UNITED STATES PATENT OFFICE.

DAVID MAXWELL, OF DETROIT, MICHIGAN.

METAL REINFORCE FOR CONCRETE AND BLANK THEREFOR.

No. 859,313.

Specification of Letters Patent.

Patented July 9, 1907.

Application filed May 21, 1906. Serial No. 317,871.

To all whom it may concern:

Be it known that I, DAVID MAXWELL, of Detroit, Wayne county, Michigan, have invented a new and useful Metal Reinforce for Concrete and Blank Therefor, of which the following is a full, clear, and exact description, reference being had to the accompanying drawings, forming part of this specification, in which—

Figure 1 is a side elevation of a reinforce made in accordance with my invention; Fig. 2 is a side view of one end portion of the blank showing the cuts therein, the manner in which the parts are bent being shown by dotted lines; Fig. 3 is an end view of the blank; and Figs. 4 and 5 are similar views showing modified forms of blanks.

15 The object of my invention is to provide a reinforce which can be cut and bent from a rolled bar or shape, its intermediate portion having an increased cross-section, and the surplus metal utilized for reinforcement above the neutral axis near the center; also to provide 20 a novel form of rolled blank from which the reinforce can be made by simple cutting and bending operations.

In the accompanying drawings, the numerals 2, 3, 4 and 5 designate a series of parallel bars which are connected at their central portions by integral webs 6, 25 the end portions of the bars 3, 4 and 5 being bent upwardly in opposite directions to form the oblique brace members 7, and the upper end portions of the brace members of the bars 4 and 5 being bent horizontally in opposite directions to form the reinforcing 30 members 8, above the neutral axis of the reinforce.

In making the reinforce shown in Fig. 1, I first roll a blank or shape of the form and cross-section indicated in Fig. 3, consisting of the parallel bar members 2, 3, 4 and 5 united by the connecting webs 6 in the central 35 plane of the bars. I then cut away or shear the webs 6 in the manner shown in Fig. 2, and bend the end portions of the bars at such cut-away portions to form the braces 7 and upper reinforcing members 8.

The bars may be of any suitable shape in cross-section, such as the flat oblong shown in Fig. 3, the square or rhomboid shown in Fig. 4, or the approximate circle shown in Fig. 5, or any other desired shape. Any desired number of the bars may be used according to the 40 length of the reinforce.

45 It will be noted that the construction above described provides for an increase in the cross-section of the reinforce at its central portion, and that the surplus material, beyond what is necessary to form the brace members, is utilized to form reinforcing members above the neutral axis of the reinforce at its central portion.

Various modifications may be made without depart-

ing from the spirit and scope of my invention, since What I claim is.

1. A metal reinforce for concrete structures consisting 55 of a lower member or chord composed of a plurality of parallel bars in substantially the same vertical plane and connected by integral webs at their intermediate portions, their end portions being separated and bent to form braces, and some of said braces being bent backwardly towards 60 the center of the reinforce; substantially as described.

2. A metal reinforce for concrete structures consisting of a lower member or chord composed of a plurality of parallel bars in substantially the same vertical plane and connected by integral webs at their intermediate portions, 65 their end portions being separated and bent to form braces, and some of said braces being bent backwardly towards the center of the reinforce above the neutral axis of the reinforce; substantially as described.

3. A metal reinforce for concrete structures consisting 70 of a lower member or chord composed of a plurality of parallel bars in substantially the same vertical plane and connected by integral webs at their intermediate portions, their end portions being separated and bent to form braces, and some of said braces being bent backwardly towards 75 the center of the reinforce, the backwardly-bent portions being of different lengths; substantially as described.

4. A metal reinforce consisting of a lower member or chord composed of a plurality of superimposed bars integrally united at their central portions and separated at 80 their end portions, the separated portions of some of the bars being bent horizontally to form an upper chord above the central portion of the lower chord; substantially as described.

5. A metal reinforce composed of at least three superimposed bars integrally united at their central portions and separated at their end portions, the separated end 85 portions being formed into an upper chord extending over the central portion of the lower chord; substantially as described.

6. A metal reinforce having a lower chord composed of at least three members integrally connected at their central portions and separated at their end portions, one of 90 said members having its end portions bent to form separated members of an upper chord, and a second member bent to complete the said chord; substantially as described.

7. A metal reinforce having a lower chord composed of a plurality of members integrally connected at their central portions and separated at their end portions; said end 100 portions being bent to form oblique braces extending in opposite directions at opposite sides of the center of the chord, and some of said braces being bent backwardly towards the center of the reinforce to constitute an upper chord; substantially as described.

8. A metal reinforce composed of a lower member or chord having a plurality of parallel cuts or slits in its end portions, the cut or slit portions being bent upwardly and then backwardly toward the center of the reinforce to form an upper chord; substantially as described.

In testimony whereof, I have hereunto set my hand.

DAVID MAXWELL.
